WILLIAM WEBB, OF WATERBURY, CONNECTICUT, ASSIGNOR TO THE
SCOVILLE MANUFACTURING COMPANY, OF SAME PLACE.

Letters Patent No. 65,972, dated June 18, 1867.

IMPROVEMENT IN HINGES FOR LAMP-BURNERS.

The Schedule referred to in these Letters Patent and making part of the same.

TO ALL WHOM IT MAY CONCERN:

Be it known that I, WILLIAM WEBB, of Waterbury, in the county of New Haven, and State of Connecticut, have invented a new and improved Hinge; and I do hereby declare that the following is a full, clear, and exact description thereof, which will enable those skilled in the art to make and use the same, reference being had to the accompanying drawings, forming part of this specification.

The present invention relates to a new and improved hinge, especially designed to be used for hinging the holders for the chimneys of coal-oil or kerosene lamps to the tops of such lamps; and this invention consists in so constructing the said hinge as to produce a stop or rest for the chimney-holder as it is swung up and away from the wick-tube for trimming or lighting the wick, or for any other reason. In the accompanying plate of drawings my improved hinge is illustrated—

Figure 1 being an enlarged perspective view of the same detached from the top of a lamp.

Figure 2, a side view of a lamp top having its chimney-holder hinged to it with a hinge made according to the present invention; and

Figures 3 and 4, detail views of the plates from which the hinge is made.

A, in the drawings, represents the hinge, and B and C its two leaves or wings, that are arranged and hung upon a common pin, *a*, so as to be opened from and closed upon each other, as in ordinary hinges. One of these leaves C is provided with a portion or arm, D, projecting from its butt, which arm is made of one and the same piece of metal with the leaf C, and, when the hinge is used for hinging the chimney-holder of a lamp to its top or cap, acts as a stop or rest for the said chimney-holder as it is swung up and away from the lamp top to enable the wick of the lamp to be trimmed or lighted, or for any other desired reason. In fig. 3 is shown the plate or sheet of which the leaf B of the hinge is composed, this plate being first cut out in the form shown, and then folded by its two ends over and upon each other at its centre line, forming at its folded edge the necessary tube shape to receive the pin or spindle *a* of the hinge. The plate shown in fig. 4 constitutes the other leaf C of the hinge when folded by its ends over and upon each other, the portion I of such plate, embraced between its shouldered ends J, forming the tube or sleeve for the hinge-pin, and the projecting stop-piece or arm the rest for the chimney-holder when swung up so as to come to a bearing upon the same, the leaf C of the hinge thus provided with a projecting stop-piece being secured or fixed to the upper edge of the lamp top, and the other leaf, B, to the under edge of the chimney-holder portion of such top. By bending the projecting stop-piece of the hinge A either up or down, the extent to which the chimney-holder can be swung up from the lamp top may be regulated at pleasure, as is obvious without any further explanation.

I claim as new, and desire to secure by Letters Patent—

The hinge A, having one of its leaves provided with a projecting rest or stop-piece, D, and made substantially as herein described and for the purpose specified.

WILLIAM WEBB.
